UNITED STATES PATENT OFFICE.

MORRIS OXENHANDLER, OF BROOKLYN, NEW YORK.

ROTARY DIE PRESS.

Application filed October 5, 1926. Serial No. 139,742.

This invention relates to processes for cutting, stamping, embossing or printing, and has particular reference to a die press which is especially designed for cutting, stamping, 5 or embossing heavy stock, such as cardboard or the like.

Heretofore presses of this type have generally operated upon the principle of the Gordon printing press whereby the die supports are fulcrumed and moved toward each other or the stock support and die are similarly moved toward each other. This principle necessarily requires considerable power, limits the speed of operation and hence production, makes for undue vibration and impairs registration.

The present invention comprehends a press of the character set forth in which the die support or one of the die supports is reciprocatory and the other die support or stock support is of the multifaced rotary type to successively dispose the faces supporting the stationary die or the stock in registry with the movable or reciprocating die.

The invention furthermore aims to provide a press of the character set forth which includes a multifaced non-reciprocating rotary member and a driven reciprocatory co-acting die support with coacting means carried by said elements for driving and rotating the rotary member from the reciprocating member.

More specifically the means for driving the rotary member from the driven reciprocating member includes a cam roller and cam groove, said cam groove including offset portions corresponding to the number of faces on the rotary multifaced member, which allows for relative movement of the reciprocating member to the non-reciprocating member after the faces are in parallel relation, and which cam groove also includes means for limiting the rotation of the rotary member to rotation in one direction.

The invention furthermore contemplates a press of the character set forth which is comparatively simple in its construction and mode of operation; compact, whereby the same occupies a minimum amount of space; inexpensive to produce and install, and which is highly efficient in its use.

With the above recited and other objects in view, reference is had to the following specification and accompanying drawings in which there is exhibited one example or em-

bodiment of the invention which is in no way intended as a limitation upon the scope of the appended claims as it is to be clearly understood that variations and modifications which properly fall within the scope of said claims may be resorted to when found expedient.

In the drawings—

Figure 1 is a side view of a press constructed in accordance with the invention;

Fig. 2 is a transverse sectional view therethrough taken approximately on the line 2—2 of Fig. 1;

Fig. 3 is a fragmentary sectional view taken approximately on the line 3—3 of Fig. 2;

Fig. 4 is a fragmentary detail sectional view taken approximately on the line 4—4 of Fig. 3;

Fig. 5 is a fragmentary perspective view of the rotary non-reciprocating member;

Fig. 6 is a diagrammatic side view.

Referring to the drawings by characters of reference, the press includes a frame including laterally spaced side members 10—10 provided at their upper ends with aligned bearings 11—11 in which a crank shaft 12 is journaled, the side members below the bearings 11 having substantially vertical guides 13 within which a cross head 14 is mounted for reciprocation. The crank shaft is provided with an offset crank portion 15 which is connected by a connecting rod 16 to a cross head 14 for reciprocating the cross head upon rotation of the crank shaft 12, which crank shaft has connected therewith a suitable driving pulley 17. The cross head constitutes a support for a suitable cutting, stamping or embossing die 18 which is attached to its lower face.

Mounted on a transverse shaft 19 in the frame is a rotary non-reciprocating multifaced drum 20, which drum or bed member presents a plurality of substantially flat faces 21 for supporting either a coacting die or the stock to be cut, stamped, embossed or printed. In order to revolve or rotate the drum so as to successively dispose the face 21 in a plane parallel to the under face of the cross head 14, a cam groove 22 is formed on one or both end walls of the drum and a cam roller or rollers 23 are each carried by the cross head for operative engagement with the groove or grooves. The cam groove is formed with angularly disposed portions 24 and 25 coinciding with the num-

ber of drum faces 21 and disposed at an angle to said faces. The juncture of the inner end of each portion 24 with the portion 25 is formed with a radial inwardly 5 projecting offset 26 and the juncture of the outer end of each portion 24 and 25 is formed with a radial outwardly projecting offset 27. The inner offsets 26 allow for the final movement of the cross head toward the 10 faces 21 while the drum is at rest and while said faces are parallel with the under face of the cross head. The offsets 27 constitute means which permits the cross head to move to the outer limit of its stroke while the drum is temporarily at rest and prior to the engagement of the cam roller in the next 15 succeeding groove portion 24. In order to positively prevent retrograde movement of the drum and to insure movement of the 20 same in one direction only, a spring-pressed abutment 28 is provided in the cam groove at the juncture of the portions 24 and 25 with each other and at a point immediately in advance of the offsets 26 and 27. The 25 spring-pressed abutments are formed with inclined or cam faces 29 which allow the cam roller to ride over the abutments for depressing the same within the recesses 30 formed in the end walls of the drum coincident with the cam grooves.

In order to lock and hold the drum in a fixed position during the final advancement of the cross head toward the faces, the cross head is provided with keeper lugs 31 engageable in keeper recesses 32 in the end walls of the drum. In order to allow for 35 adjustments in the stroke of the cross head to compensate for variations in the thickness of the stock being operated upon, the cross head is adjustably connected to the link 16 by means of an element 33 in which the wrist pin 34 is mounted, which element 33 is provided with slotted portions 35. Bolts 36 extend through the slots and are anchored in the cross head. The element 40 45 33 has swiveled therein an adjusting screw 37 which engages in a threaded socket 38 in the cross head. In order to compensate for this adjustment the cam roller arms 39 are adjustably connected to the cross head by 50 adjusting screws 40 extending through threaded bearing lugs 41 in the cam roller arms 39.

In use and operation, the operator feeds 55 the stock on to the face 21 of the drum immediately preceding the face which is disposed in the path of movement of the die member and as the die member and cross head is reciprocated, the drum is rotated toward the cross head carrying the face with 60 the stock superimposed thereon into position whereby upon movement of the cross head toward said face the keeper lugs 31 engage in the keeper recesses 32 to lock the drum against rotation while the die member is be-

ing forced into engagement with the stock. During this final advancement, it is obvious that the cam roller moves into the offset portion 26 of the cam groove so that temporarily no motion is imparted to the drum and proper registration is insured. It is also obvious that during the initial retraction of the cross head from the face of the drum, the cam roller imparts no motion to the drum until the keeper lugs are disengaged 70 from the keeper recesses. After this disengagement, the cam roller engages with the walls of the angular portion 25 of the grooves to again impart rotary movement to the drum. As the cam roller advances toward the outer end of the portion 25, it engages the inclined or cam face 29 of the spring-pressed abutment 28, depressed and rides beyond said abutment and enters the outer radial offset 27. When the change of 75 direction of the stroke of the cross head occurs, the cam roller is shunted into the next adjacent angular portion 24 of the cam grooves, due to the fact that the abutment element 28 insures movement in this direction.

Having thus described my invention, I claim:

1. In a die press, mechanism for imparting intermittent rotation to a multifaced non-reciprocating rotary member from a driven reciprocating member, said mechanism consisting of a cam roller on one of said members and a cam groove formed in the other member within which the roller engages, said cam groove having angularly disposed portions corresponding in number to the number of faces on the rotary member.

2. In a die press, mechanism for imparting intermittent rotation to a multifaced non-reciprocating rotary member from a driven reciprocating member, said mechanism consisting of a cam roller on one of said members and a cam groove formed in the other member within which the roller engages, said cam groove having angularly disposed portions corresponding in number to the number of faces on the non-reciprocating rotary member, and alternate rotary inner and outer offsets at the juncture of the angular portions to permit of partial strokes of the reciprocating member while the rotary member is at rest.

3. In a die press, mechanism for imparting intermittent rotation to a multifaced non-reciprocating rotary member from a driven reciprocating member, said mechanism consisting of a cam roller on one of said members and a cam groove formed in the other member within which the roller engages, the cam groove having angularly disposed portions corresponding to the number of faces on the non-reciprocating rotary member, the cam grooves adjacent the junc- 130

ture of the angularly disposed portions having spring-pressed depressible abutments cooperating with the cam roller to prevent retrograde movement of the rotary member 5 and to insure rotation of the rotary member in one direction only.

4. In a die press, mechanism for imparting intermittent rotation to a multifaced non-reciprocatory rotary member from a 10 driven reciprocatory member, said mechanism consisting of a cam roller on one of said members and a cam groove formed in the other member within which the roller engages, the cam groove having angularly

disposed portions corresponding to the number of faces on the rotary member, and alternate radial inward and outward offsets at the juncture of the angular portions to permit of portional strikes of the reciprocatory member while the rotary member is at 15 rest, the rotary and reciprocatory member having co-acting means adapted to lock the rotary member against relative turning movement during the final portion of the stroke of the reciprocatory member toward 20 the rotary member.

MORRIS OXENHANDLER.
